IGNITION AND FUEL CONTROL MEANS FOR LIQUID FUEL BURNERS

Marc Resek, Shaker Heights, Wilbur A. Schultz, Lakewood, and Lloyd V. Antl, Cleveland, Ohio, assignors to Perfection Stove Company, Cleveland, Ohio, a corporation of Ohio

Original application June 16, 1950, Serial No. 168,524. Divided and this application August 14, 1951, Serial No. 241,866

7 Claims. (Cl. 236—1)

This application is a division of one filed by us on June 16, 1950, Serial No. 168,524, and the invention that constitutes the subject matter of the present case is an electrical ignition and control means for liquid fuel burners, particularly of the vaporizing class, disclosed in the original application.

An object of the present invention is the provision of an electrical control system, desirably including a sheathed, embedded electrical igniter, for liquid fuel burners, especially of the type aforesaid, that renders the burner entirely automatic in operation and thoroughly reliable and safe.

Another object of the invention is to provide an electrical control system for liquid fuel burning apparatus that insures a safe condition of the apparatus in case of current failure.

Another object is to provide an electrical ignition and control means for liquid fuel burners having a low rate of current consumption.

One advantage arising from the use of an electrical igniter of the kind above described and which permits the use of a high capacity resistance element is that the igniter may be supplied with current directly from the regular 110 volt house potential, thus eliminating the need of an ignition transformer, such as is employed with exposed hot wire or spark gap igniters.

The foregoing objects and advantages are realized in the embodiment of the invention illustrated in the accompanying drawing wherein the figure represents a sectional side elevation of liquid fuel burning apparatus equipped with the electrical ignition and control means of our invention, schematically illustrated.

Proceeding with a more detailed description of the invention wherein the parts disclosed in the drawing will be referred to by reference characters, 1 denotes, generally, a burner pot or bowl that is incorporated in the liquid fuel burning apparatus. 2 designates, generally, an air housing that surrounds the burner pot or bowl, and a casing 3, shown in broken lines, surmounts and is in operative relation to the pot or bowl and encloses a combustion space or chamber C.

The burner pot includes a perforated cylindrical peripheral wall 5, and a slightly dished circular bottom wall 6, the latter being shown as formed integral with the peripheral wall. Attached to the exterior of the pot at about the junction of the walls 5 and 6 is a continuous annular overflow trough 8 which communicates with the interior of the pot through the lowest row of perforations, designated 10. The peripheral wall 5 is provided with a relatively large opening 12, and secured to said wall about the opening, preferably by welding, is the inner end of the cylindrical neck 15 that terminates at its outer end in a flange 16.

Welded or otherwise secured to the outwardly flared upper end of the peripheral wall 5 of the burner pot 1 is a generally upwardly convergent annular top wall 18, and shown as likewise secured to the edge portion of said top wall about the relatively large opening therein is the base flange of a perforated neck 20. This neck is shown as flared outwardly and thence upwardly to provide a peripheral flange that is secured to an upstanding flange of a ring-like member 23. Toward its outer edge said member is stepped abruptly upwardly to provide a vertical cylindrical shoulder 24, outwardly beyond which the member is provided with a broad flat flange 25 that

is adapted to be engaged with the underside of an annular bottom wall 28 of the casing 3, and to be detachably secured thereto by fastening means or bolts 29.

The air housing 2 includes a cylindrical peripheral wall 30 and a circular bottom wall 31, formed to fit a suitable distance within the lower end of the peripheral wall. These walls are suitably secured together, by welding or other means, and attached to the upper end of the peripheral wall 30 is a top member 32, shown as extending inwardly and thence upwardly and as fitted to the shoulder 24 of the previously described ring-like member 23, the parts being fastened together, preferably by welding. Opposite the neck 15 of the burner pot, the wall 30 is provided with a large opening 35 and welded or otherwise secured to said wall about the opening 35 is the inner end of a sleeve 36. A suitable distance from its outer end, the sleeve 36 is provided with an internal flange 38 formed, in the present instance, of an annular member that is L-shaped in cross section and a cylindrical portion of which is welded or otherwise secured to the sleeve. Attached by suitable fastening means 40, such as screws, to the flange 16 of the neck 15, are the peripheral portions of circular plates 42 and 44, with a gasket 45 of packing material interposed between the latter plate and the flange 16. By reason of their function, these plates will be referred to, respectively, as the nozzle plate, and the igniter plate. These plates are provided with relatively large registering openings, and shown as fitted within the opening of the nozzle plate 42 is the outer end of a cup-like shell 50, which we shall refer to as the outer shell, said shell and plate being secured together, desirably by welding. 52 denotes a nozzle guide. It consists of a cylindrical body that is reduced in diameter adjacent its lower end, and said end occupies a circular aperture in the lower side of the shell 50, the parts being welded or otherwise rigidly connected together. 55 denotes an inner shell that is nested within and spaced from the outer shell and is provided with an aperture on its under side wherein is fitted the bottom portion of the larger end of the nozzle guide 52. The inner shell is also welded or otherwise firmly secured to the nozzle guide and is supported solely thereby. It may be explained that the nozzle guide has an axial passage that is enlarged at its upper end and is made convergent at its lower end, as will be seen by reference to the original application above identified. The discharge end of a nozzle 62 is located within and centrally of the nozzle guide. At its upper end the nozzle is provided with a lateral extension that is communicatively connected, by a conventional coupling 63, to the adjacent end of a fuel supply pipe 65.

70 denotes a sheathed electrical igniter, which may be described, briefly, as consisting of a current carrying element or wire that is embedded in refractory insulating material of high heat conductivity encased in a tube of heat resisting metal, from which said element or wire is electrically insulated by said refractory material. The inner end portion of the igniter is shown as in the form of a coil, and the terminal portions thereof extend through aligned holes in the plates 42 and 44, and are welded or otherwise secured to the plate 44 which has heretofore been referred to as the igniter plate. Forwardly of the plate 42, the terminal portions of the igniter are provided with binding posts, one being shown and designated 75 in the drawing. A baffle 80 is suitably attached to the igniter and includes a bottom wall 81 that extends beneath the coil of the igniter, and a relatively steep inclined wall portion 83 that is disposed in substantially vertical alignment with the nozzle 62 so that fuel descending by gravity from the nozzle will impinge against said inclined wall portion.

Liquid fuel is supplied to the burner pot through a so-called constant level control valve, shown in a conventional manner in the drawing and designated 90. It consists of a receptacle to which fuel is conveyed from a suitable source (not shown) by a pipe 92, under the control of a valve 93 that is closed by a float 94, whereby it has the usual operative connections, when fuel rises within the receptacle a given distance. While these float controlled valves are reasonably reliable, they are subject to leakage, and for that reason, as will presently

appear, we do not rely upon this float controlled valve to positively shut off the flow of fuel to the burner. Also incorporated in this unit that is now under consideration is a metering valve 98 that reciprocates within a hollow boss that rises from the bottom of the receptacle and through which communicative connection is established between the interior of the receptacle and the previously mentioned fuel supply pipe 65 that leads to the nozzle 62. Included in this pipe is a so-called fuel release valve 100 of the well known solenoid operated type, the solenoid and valve being shown in a conventional manner in dotted lines. The valve is biased toward closed position and accordingly shuts off the flow of fuel when the solenoid is deenergized. Reversely, so long as current flows through the coil of the solenoid, the valve will be held open. 102 denotes a similar inlet valve in the pipe 92 which functions when the current is cut off to positively arrest flow of fuel to the constant level control valve 90. As an emergency measure, so that the burner will operate on low fire in case of a general power failure, a by-pass 103 is provided in each of the pipes 65 and 92 about the respective valves 100 and 102 therein, each by-pass, in turn, being equipped with a manual valve 104.

Any liquid fuel that overflows, under abnormal conditions, from the burner pot 1 into the trough 8 is conveyed through a pipe 105 to a closed vessel 106 from which a tube 107 rises through the bottom of the receptacle of the constant level control valve 90 and terminates therein above maximum liquid level. A float 110 operates within the vessel 106 and a rod 111 rises from said float through the tube 107 and is maintained by the latter with its upper end in vertical alignment with a finger 112 on the float 94. Accordingly, when overflow fuel rises to a sufficient height within the vessel 106 to accomplish such end, the float 110 ascends and lifts the rod 111 so as to engage its upper end with the finger 112 and prevent the float 94 from dropping and lifting the valve 93 from its seat. By this means normal feed of fuel to the burner is prevented until the vessel 106 is drained by the opening of a valve 114 adjacent the bottom of the latter.

120 designates an air impeller or centrifugal blower that supplies combustion air to the burner. The outlet of the casing of the air impeller or blower 120 fits within the sleeve 122 that is carried by and extends through an opening in a disc or plate 125, and to which said sleeve is rigidly secured, as by welding. The disc or plate 125 is flanged about its edge and fits within the outer end of the sleeve 36 against the previously mentioned flange 38 to which it is secured by a plurality of fastening means 126. The plate 125 is provided with an aperture for the accommodation of the fuel supply pipe 65. A damper 127, of common and well known type, is desirably located in the outlet of the casing of the air impeller or blower and by means of which the quantity of combustion air supplied to the apparatus may be regulated.

The electrical system of our present invention by means of which the operation of the above described liquid fuel burning apparatus is automatically controlled includes, besides the solenoids of the valve 100 and 102, the following parts: a transformer 130, the primary and secondary windings of which are designated 131 and 132, respectively; a room thermostat 135 that is shown conventionally as comprising a thermosensitive element of the bimetal variety 136 through which, and a leaf 137 that is carried thereby, a current is adapted to be conducted to the "low fire" contact 138, and the "high fire" contact 139; a so-called Micro switch 140, the movable element 141 of which is biased in a direction to engage a contact 142, and which is movable into engagement with a contact 143 through the intervention of a push rod 144. Said push rod has operative connection at its lower end with a leaf spring 145, as by bearing thereon, and under certain conditions that will hereinafter appear this leaf spring serves as an electrical conductor, wherefore, in certain of the claims, it is termed "a current carrying resilient member." 150 designates, generally, a switch including blades 151 and 152 that are mechanically connected by an extension 153 of the core of a solenoid 155. A bimetal strip 158 has operative connection with the previously mentioned metering valve 98 and serves, when cold, to retain the valve open sufficiently to pass enough fuel to maintain low fire burner operation. Associated with said bimetal strip is an electric resistance heater 160, and when this heater is energized and its temperature accordingly raised, it causes the bimetal strip to warp in a direction to lift the metering valve to wide open posi-

tion, thereby to pass sufficient fuel to maintain high fire operation of the burner. Associated with the previously mentioned leaf spring 145 is a thermostatic or thermosensitive current carrying element in the form of a bimetal strip, designated 165. When this element or strip is cold it contacts the free end of the leaf spring 145 and holds the latter under tension in a position to maintain, through the intervention of the push rod 144, the movable element 141 of the Micro switch in engagement with the contact 143 thereof. When heat is imparted to the element or strip 165 by an electrical resistance heater 167, said element or strip will warp in a direction to relax the leaf spring 145 and thereafter withdraw from said spring and engage a contact 168, the latter occurring after a suitable interval of time. Relaxing of the spring 145 permits the movable element 141 of the Micro switch 140 to snap over into engagement with the contact 142.

170 designates a so-called top limit switch, a safety feature usually employed in domestic furnaces and other similar apparatus, to open the control circuit in case the apparatus becomes overheated, such switch, obviously, being disposed in intimate heat exchange relation to a suitable part of the apparatus.

The usual house circuit, furnishing electrical energy at a potential of say 110 volts, is represented by a conductor 175 that leads to the primary winding 131 of the transformer 130, and a conductor 176 that leads from said winding. The circuits of higher potential or voltages are shown in heavy lines, and those of comparatively low voltage, in light lines. The motor 180 of the air impeller or blower 120, and the igniter 70, which may have a capacity of say 750 watts, are in high voltage circuits, as will presently appear. Current is carried from the conductor 175, through a conductor designated 182, to the movable element 141 of the Micro switch 140. The contact 143 of said switch is placed in electrical connection with one side of the motor 180 through a conductor 183. The other contact 142 of said switch has electrical connection with the terminal 75 of the igniter 70 through a conductor 184. Current returns from the motor and igniter to the other side of the high voltage circuit through a conductor 185 and its respective branches 186 and 187. The low voltage circuits, say of 24 volts, that have as their source of current the secondary winding 132 of the transformer 130, will be described in connection with the operation of the apparatus.

As illustrated in the drawing, the apparatus is inactive excepting for the operation of the air impeller or blower, it being assumed that the temperature of the space to which the room thermostat 135 is subjected is above that requiring immediate low fire operation. Upon decline of said temperature to the upper limit of a temperature range for which the thermostat is set, and which may be referred to as the comfort range, the element 136 thereof will swing in a direction and only far enough to engage the leaf 137 with the contact 138. This will close a circuit (starting with the secondary winding 132 of the transformer) through a conductor 190, the winding of the solenoid of inlet valve 102, conductor 191, the beforementioned parts of the room thermostat, and a conductor 192, including the limit switch 170 back to the source. This will result in the opening of the valve 102, insuring ample fuel supply to the constant level control valve 90. Current will also flow from the conductor 190 through a conductor 195, the blade 152 of the switch 150 and a conductor 197 to the electrical resistance heater 167 and thence, through a conductor 198, to the previously mentioned conductor 191 and back to the source. Very shortly, say about ten seconds, after the energization of the heater 167 the element or strip 165 will warp enough to relax the spring 145 and permit the movable element 141 of the Micro switch 140 to snap into engagement with the contact 142, whereupon current will flow through the conductor 184 to the igniter 70, returning through the conductors 187 and 185 to the negative side of the main circuit. Withdrawal of the element 141 from the contact 143 will, of course, cut off the supply of current to the motor 180 of the air impeller or blower, thus interrupting the air supply to the burner during the ignition phase and accordingly accelerating the preheating of the igniter and adjacent parts of the burner due to the absence of the cooling effect of the air. While the element or strip 165 is warping sufficiently to engage contact 168, the igniter 70 will continue to build up heat in itself and in the adjacent parts

of the burner pot. After an interval of time, say one and one-half minutes, said element or strip 165 will engage the contact 168 and close a circuit including, besides said element and contact, conductors 200 and 201, the winding of the solenoid 155, and a conductor 202 that leads back to the previously mentioned conductor 191. Upon energization of the solenoid 155, the blades 151 and 152 of the switch 150 will be swung into engagement with the respective contacts 205 and 206, the latter blade 152 withdrawing from a contact 207 that controls the previously described circuit including the electrical heater 167, thereby opening said heater circuit. By engagement of the blade 152 with the contact 206, a circuit is established from the aforementioned conductor 195, through the blade 152, contact 206 and a conductor 208 that joins the previously mentioned conductor 201, thereby to insure continued flow of current to the solenoid 155 after the element or strip 165 cools and withdraws from contact 168. During the interval of time that represents the cooling off period of the element or strip 165, approximately one and one-half minutes, which is measured from the time said strip withdraws from contact 168 until it engages and deflects the spring 145, the igniter 70 will remain energized. There is, however, an appreciable fraction of this time, say ten seconds, when electrical contact is made between the element or strip 165 and said spring 145 before the latter yields enough to effect operation of the Micro switch. During this dwell current will flow through the conductor 210, the switch blade 151, contact 205, a conductor 212, the winding of the solenoid of the fuel release valve 100, and a conductor 213 to the previously mentioned conductor 202 and thence to the source, thus opening said valve to permit oil to flow, under the control of the metering valve 98, from the fuel supply of the constant level control valve 90 to the burner.

Now, with the igniter and adjacent parts of the burner, including the baffle 80, highly heated, the liquid fuel that drops from the nozzle 62 will impinge against the inclined wall portion 83 of the baffle 80 and practically instantaneously flash into vapor and be ignited, such fuel as remains liquid rapidly vaporizing as it flows over the bottom wall of the baffle, in contact with the igniter, or, if not before reaching this point, from the bottom of the burner pot, sufficient air being supplied through the perforations of the peripheral wall of the pot to support such combustion as now occurs.

By this time the continued movement of the element or strip 165 will have fully deflected the leaf spring 145 and, through the medium of the rod 144, operated the Micro switch 140, causing the element 141 thereof to withdraw from the contact 142 and resume engagement with the contact 143. This will cut off supply of current to the igniter and reestablish the circuit through which current is delivered to the motor 180 of the air impeller or blower 120. Air will now be supplied to the burner, desirably under the control of the damper 127, and which may be set to provide the proper amount of air to the burner to produce the best results. It will be observed that the discharge opening of the impeller or blower casing is so related to the shells 50 and 55 as to insure air circulating through the space between the shells and about the nozzle. The constant flow of air will keep said shells and nozzle and nozzle guides relatively cool, notwithstanding their proximity to the intense heat within the burner pot. Some of the air entering the shell 55 will pass through the nozzle guide about the nozzle and into the burner pot and provide primary air in the vicinity of the igniter.

Under the now prevailing conditions fuel will continue to flow to the burner in proper amount to maintain low fire. In the event the temperature of the space to which the room thermostat is subjected rises as a result of the low fire condition to a value above the upper limit of the comfort range for which the room thermostat is set, the element 36 will swing toward the position shown in Fig. 1, withdrawing the leaf 137 from the contact 138, thus opening all circuits and allowing the burner to resume the condition assumed at the beginning of the description of operation. On the other hand, should the temperature of said space, notwithstanding low fire operation, drop below the comfort range, the element 136 of the room thermostat will swing still further in its former direction, maintaining engagement of the leaf 137 with the contact 136 and, at the same time, engag-

ing its terminal portion with the contact 139, thereby to close the circuit that branches off from the previously described circuit represented in part by the conductor 212 and through which current is supplied to the solenoid 5 of the fuel release valve 100. The present circuit includes a conductor 225 that leads from the conductor 212 to the electrical resistance heater 160 that is associated with the thermosensitive element or bimetal strip 158. Continuing on from this heater, the current returns to the source through a conductor 226, contact 139, the element 136 of the room thermostat, and the conductor 192 which, as previously mentioned, contains the limit switch 170.

When the heater 160 is energized, the element or strip 158 will warp in a direction to move the metering valve 98 to wide open position, under which circumstances fuel in sufficient quantity is delivered to the burner to maintain high fire. When, under these circumstances, the temperature to which the room thermostat is exposed 15 rises to somewhere within the comfort range, under which conditions low fire operation is sufficient, the element 136 will withdraw from contact 139 and open the circuit including the heater 160, after which the element or strip 158 will cool and resume its former condition 20 to return the metering valve to the position shown in the drawing.

The valves 101 and 102, when the solenoids thereof are deenergized, serve to positively shut off the flow of fuel to the burner thereby insuring against fuel drip 25 when the room thermostat is not calling for heat. However, when said thermostat is in either of its effective 30 positions, said valves 101 and 102 are open, under which circumstances the fuel supply to the burner is regulated by the constant level control valve 90, which includes 35 the metering valve 98.

Having thus described our invention, what we claim is:

1. In combination, a liquid fuel burner, means for conducting fuel thereto, a normally closed fuel release valve in said conducting means, a solenoid for operating said fuel release valve, an electrical igniter for the burner, a transformer, a relatively high voltage circuit having a branch including the primary winding of the transformer and a second branch including the igniter, a switch in the latter branch which is movable to a first position to close said branch or to a second position to open the same, a thermosensitive current carrying element, spaced contacts associated with said element for alternate engagement thereby, operative connections between said element and the aforesaid switch 40 causing movement of the latter to first position when said element is heated and to second position when said element is cool, a resistance heater for heating said thermosensitive element, a two-blade solenoid switch including in association with the blades thereof a single contact for engagement by one blade, and a first contact and a second contact for alternate engagement by the other blade, a relatively low voltage circuit having as its source the secondary winding of the transformer, a room thermostatic switch characterized by a movable current carrying element and by a contact arranged to be engaged by said element as the element responds to a fall in temperature, the element withdrawing from said contact as said element subsequently responds to a rise in temperature, a first branch of said 45 low voltage circuit including said other blade of the solenoid switch and said first contact associated therewith, said resistance heater, the contact of the room thermostatic switch and the movable element of the latter; a second branch of the low voltage circuit including said thermosensitive current carrying element and one of said contacts associated therewith, the solenoid of said two-blade switch, and the contact and movable element of the room thermostatic switch, said second branch being closed upon response of said thermosensitive current carrying element to the heat generated by said resistance heater and the resultant engagement of said element with the contact associated with it, the last mentioned element, when heated, warping and thereby permitting movement of the first mentioned switch 50 from second to first position, said solenoid, upon being energized, moving both blades of the aforesaid two-blade switch so as to open said first branch of the low voltage circuit through the resistance heater; a third branch of the low voltage circuit including said other blade 55 of the two-blade switch and said second contact associ- 55
2. In combination, a liquid fuel burner, means for conducting fuel thereto, a normally closed fuel release valve in said conducting means, a solenoid for operating said fuel release valve, an electrical igniter for the burner, a transformer, a relatively high voltage circuit having a branch including the primary winding of the transformer and a second branch including the igniter, a switch in the latter branch which is movable to a first position to close said branch or to a second position to open the same, a thermosensitive current carrying element, spaced contacts associated with said element for alternate engagement thereby, operative connections between said element and the aforesaid switch 60 causing movement of the latter to first position when said element is heated and to second position when said element is cool, a resistance heater for heating said thermosensitive element, a two-blade solenoid switch including in association with the blades thereof a single contact for engagement by one blade, and a first contact and a second contact for alternate engagement by the other blade, a relatively low voltage circuit having as its source the secondary winding of the transformer, a room thermostatic switch characterized by a movable current carrying element and by a contact arranged to be engaged by said element as the element responds to a fall in temperature, the element withdrawing from said contact as said element subsequently responds to a rise in temperature, a first branch of said 65 low voltage circuit including said other blade of the solenoid switch and said first contact associated therewith, said resistance heater, the contact of the room thermostatic switch and the movable element of the latter; a second branch of the low voltage circuit including said thermosensitive current carrying element and one of said contacts associated therewith, the solenoid of said two-blade switch, and the contact and movable element of the room thermostatic switch, said second branch being closed upon response of said thermosensitive current carrying element to the heat generated by said resistance heater and the resultant engagement of said element with the contact associated with it, the last mentioned element, when heated, warping and thereby permitting movement of the first mentioned switch 70 from second to first position, said solenoid, upon being energized, moving both blades of the aforesaid two-blade switch so as to open said first branch of the low voltage circuit through the resistance heater; a third branch of the low voltage circuit including said other blade of the two-blade switch and said second contact associ- 75
3. In combination, a liquid fuel burner, means for conducting fuel thereto, a normally closed fuel release valve in said conducting means, a solenoid for operating said fuel release valve, an electrical igniter for the burner, a transformer, a relatively high voltage circuit having a branch including the primary winding of the transformer and a second branch including the igniter, a switch in the latter branch which is movable to a first position to close said branch or to a second position to open the same, a thermosensitive current carrying element, spaced contacts associated with said element for alternate engagement thereby, operative connections between said element and the aforesaid switch 80 causing movement of the latter to first position when said element is heated and to second position when said element is cool, a resistance heater for heating said thermosensitive element, a two-blade solenoid switch including in association with the blades thereof a single contact for engagement by one blade, and a first contact and a second contact for alternate engagement by the other blade, a relatively low voltage circuit having as its source the secondary winding of the transformer, a room thermostatic switch characterized by a movable current carrying element and by a contact arranged to be engaged by said element as the element responds to a fall in temperature, the element withdrawing from said contact as said element subsequently responds to a rise in temperature, a first branch of said low voltage circuit including said other blade of the solenoid switch and said first contact associated therewith, said resistance heater, the contact of the room thermostatic switch and the movable element of the latter; a second branch of the low voltage circuit including said thermosensitive current carrying element and one of said contacts associated therewith, the solenoid of said two-blade switch, and the contact and movable element of the room thermostatic switch, said second branch being closed upon response of said thermosensitive current carrying element to the heat generated by said resistance heater and the resultant engagement of said element with the contact associated with it, the last mentioned element, when heated, warping and thereby permitting movement of the first mentioned switch from second to first position, said solenoid, upon being energized, moving both blades of the aforesaid two-blade switch so as to open said first branch of the low voltage circuit through the resistance heater; a third branch of the low voltage circuit including said other blade of the two-blade switch and said second contact associ- 85

ated therewith, the solenoid of the two-blade switch and the contact and movable element of the room thermostatic switch; and a fourth branch of said low voltage circuit including said thermosensitive current carrying element and the other contact associated therewith, the said single contact and the corresponding blade of the two-blade switch, the solenoid of the fuel release valve and the contact and movable element of the room thermostatic switch, the aforesaid thermosensitive current carrying element functioning with delayed action to open said second branch of the low voltage circuit and thereafter to close the fourth branch, the final movement of the thermosensitive current carrying element, upon becoming cool, causing movement of the first mentioned switch from first to second position, the room thermostatic switch opening all branches of the low voltage circuit when its movable element withdraws from the contact thereof.

2. In combination, a liquid fuel burner, means for conducting fuel thereto, a normally closed fuel release valve in said conducting means, a solenoid for operating said fuel release valve, an electrical igniter for the burner, an air impeller for supplying combustion air to the burner, an electric motor for operating said impeller, a transformer, a relatively high voltage multiple branch circuit including in one branch thereof the primary of the transformer, two other branches of said high voltage circuit including, respectively, the igniter and the motor, a switch controlling the latter branches of said circuit movable to a first position to supply current to the igniter and to a second position to supply current to the motor, a current carrying resilient member provided with a contact, operative connections between said member and the aforesaid switch causing movement of the latter to first position when said member is in relaxed condition and to second position when the member is placed under tension, a thermosensitive current carrying element occupying a position, when cold, to engage the contact of said resilient member and hold said member under tension, and movable to a second position when heated to withdraw from said contact and permit the member to relax, a second contact associated with said thermosensitive current carrying element and engaged thereby when the element is sufficiently heated, a resistance heater for heating said thermosensitive element, a two-blade solenoid switch including in association with the blades thereof a single contact for engagement with one blade, and a first contact and a second contact for alternate engagement by the other blade, a relatively low voltage circuit having as its source of electrical energy the secondary of the transformer, a room thermostatic switch in series circuit with said secondary and characterized by a movable current carrying element and by a contact arranged to be engaged by said element as the element responds to a fall in temperature, the element withdrawing from said contact as said element subsequently responds to a rise in temperature, a first branch of said low voltage circuit including said other blade of the solenoid switch and said first contact associated therewith, said resistance heater, and the contact and movable current carrying element of the room thermostatic switch; a second branch of the low voltage circuit including said thermosensitive current carrying element, the current carrying resilient member, the solenoid of said two-blade switch, and the movable current carrying element and contact of the room thermostatic switch, the second branch circuit being closed upon response of said thermosensitive current carrying element to the heat generated by said resistance heater, the last mentioned element, when heated, withdrawing from the contact of said resilient member, thereby to permit relaxing of the latter and the resultant movement of the first mentioned switch from second to first position, said solenoid, upon being energized, acting to withdraw said other blade from said first contact associated therewith and open said first branch of the low voltage circuit, a third branch of the low voltage circuit which includes said other blade and said second contact associated therewith, the solenoid of the two-blade switch and the movable current carrying element and contact of the room thermostatic switch; a fourth branch of the low voltage circuit adapted to be closed by action of said two-blade switch when the solenoid thereof is energized to cause said single contact to be engaged by the corresponding blade, and which fourth

branch circuit includes the thermosensitive current carrying element, the aforesaid resilient member, the said single contact and corresponding blade of the two-blade switch, the solenoid of the fuel release valve, and the movable current carrying element and contact of the room thermostatic switch, the aforesaid thermosensitive current carrying element functioning to open the second branch circuit (that is closed by said element when heated) and thereafter, with delayed action, engaging the contact of the resilient member; the final movement of the thermosensitive current carrying element, upon becoming cool, placing said resilient member under tension thereby to cause movement of the first mentioned switch from first to second position, all branch circuits being open when the movable element of the room thermostatic switch withdraws from the contact of the latter.

3. The combination and arrangement of parts defined by claim 2, and, in addition thereto, a constant level valve in said fuel conducting means, a metering valve that controls the outlet of fuel from said constant level valve and which normally occupies a position to pass sufficient fuel for low fire operation, and movable to a second position to increase the amount of fuel passed to produce high fire operation; a thermostatic element having operative connection with the metering valve and moving, when heated, in a direction to shift the metering valve to second position; an electrical resistance heater for heating said thermostatic element; a second contact incorporated in the room thermostatic switch that is engaged by the movable current carrying element of said switch after engagement thereby of the first contact, as the element responds to a further fall in temperature, the element withdrawing from said contacts in reverse order as said element responds to a rise in temperature, and a further branch of the low voltage circuit including said resistance heater and the second contact and the movable current carrying element of the room thermostatic switch.

4. The combination and arrangement of parts defined by claim 3, and, in addition thereto, a normally closed solenoid inlet valve for controlling the supply of fuel to the constant level valve, and a further branch of the low voltage circuit including the solenoid of said inlet valve and the first contact and the movable current carrying element of the room thermostatic switch.

5. In combination, a liquid fuel burner, means for conducting fuel thereto, flow control means in said fuel conducting means, an electrical actuator for said flow control means, an electrical igniter, a transformer, a relatively high voltage circuit having a branch including the primary winding of the transformer and a second branch including the igniter, a switch in said second branch movable to a first position to close said branch and to a second position to open the same, a time delay device incorporating a thermosensitive warp element, an electrical heater for supplying heat to said element, operative connections between said warp element and the aforesaid switch causing movement of the latter to first position when said element is heated and to second position when said element is cool, a second switch including a first contact and a second contact relatively movable into engagement with each other and a third contact and a fourth contact together with a fifth contact relatively movable alternately into engagement with the third and fourth contacts, a second electrical actuator for operating the second switch to simultaneously effect engagement of the first and second contacts and the third and fifth contacts, and, alternately, to effect engagement of the fourth and fifth contacts, a control circuit having as its source the secondary winding of the transformer, a third switch characterized by a thermosensitive element and by relatively movable contacts with at least one of which said element has operative connection and that are caused thereby to engage each other when the element responds to a drop in temperature and to separate when said element responds to a rise in temperature, a first branch of said control circuit including the third and fifth contacts of the second switch, said electrical heater, and the contacts of the third switch; two circuit closing means operatively associated with the aforesaid thermosensitive warp element and alternately rendered effective thereby to close circuits when said warp element is heated and is permitted to cool, respectively, a second branch of the control circuit including

the first of said circuit closing means, the second electrical actuator and the contacts of the third switch, said second branch being closed upon response of said thermosensitive warp element to the heat generated by said electrical heater, the last mentioned element, when heated, warping and thereby permitting movement of the first mentioned switch from second to first position, the second electrical actuator, upon being energized, causing separation of the third and fifth contacts of the second switch thereby to open the first branch of the control circuit and establish contact between the first and second contacts and between the fourth and fifth contacts of said second switch; a third branch of the control circuit including the fourth and fifth contacts of the second switch, the second electrical actuator, and the contacts of the third switch; and a fourth branch of the control circuit including the second circuit closing means associated with the thermosensitive warp element, the first and second contacts of the second switch, the first mentioned electrical actuator, and the contacts of the third switch, said thermosensitive warp element functioning with delayed action to open the second branch of the control circuit and thereafter to close the fourth branch, the final movement of the warp element, upon cooling, causing movement of the first mentioned switch from first to second position, the contacts of the third switch separating, when the thermosensitive element of said third switch becomes sufficiently heated to effect such action, thereby to open all branches of the control circuit.

6. The combination and arrangement of parts defined by claim 5, and, in addition thereto, an air impeller for supplying combustion air to the burner, an electric motor for operating said impeller, a third branch of the relatively high voltage circuit including said motor, and

30
35

contact means also included in said branch and operatively associated with the first mentioned switch so as to be actuated thereby when said switch assumes second position to close the third branch of the high voltage circuit.

7. The combination and arrangement of parts defined by claim 5, and, in addition thereto, a second set of relatively movable contacts incorporated in the third switch that are caused to engage, after engagement of the other contacts of said switch, by action of the thermosensitive element of said switch in its response to a further drop in temperature and that are caused to separate, before disengagement of said other contacts, by reverse action of said element, a constant level valve in said fuel conducting means, a metering valve that controls the outlet of fuel from said constant level valve and which normally occupies a position to pass sufficient fuel for low fire operation, and movable to a second position to increase the amount of fuel passed to produce high fire operation; a thermostatic element having operative connection with the metering valve and moving, when heated, in a direction to shift the metering valve to second position; an electrical resistance heater for heating said thermostatic element, and a further branch of the control circuit including said resistance heater and the second set of contacts of the third switch.
